FOLDING APPARATUS AND METHOD

Maurice M. Balsam, New York, N. Y., assignor
to William L. Lawson, New York, N. Y.

Application May 20, 1936, Serial No. 80,683

24 Claims. (Cl. 93—39.1)

This invention relates to novel apparatus and method for folding a blank of sheet material and more particularly to apparatus and method for folding a hollow blank of sheet material to form 5 said blank into a bellows.

One object of my invention is to fold the material into a form such as a bellows, rapidly and accurately along predetermined lines.

A further object of my invention is to provide 10 compact and efficient apparatus, which may be easily operated, for performing folding operation.

Another object is to compress the folds of sheet material after the folding operation has been initiated, in order to obtain a creasing action.

15 Further objects and advantages of my invention will be apparent from the following description of one embodiment thereof illustrated in the drawings, in which

Fig. 1 is an elevation of the left side of a complete machine for performing the folding operations.

Fig. 2 is a horizontal sectional view illustrating the head of the machine in plan on an enlarged scale and taken on the line 2—2 of Fig. 1.

25 Fig. 3 is a vertical section taken diagonally through the head of the machine on about the line 3—3 of Fig. 2 with certain parts broken away to better illustrate the construction.

Fig. 4 is a vertical section, similar to Fig. 3, 30 but showing the movable parts of the head of the machine in an intermediate position.

Fig. 5 is a view similar to Figs. 3 and 4 but showing the folding mechanism in the position, occupied at the completion of the folding operation, and before release.

35 Fig. 6 is a horizontal section taken on about the line 6—6 of Fig. 3.

Fig. 7 is a foreshortened vertical section of one detail of the mechanism taken on the line 40 7—7 of Fig. 3.

Fig. 8 is a horizontal sectional view of the mechanism illustrated in Fig. 7 and taken on the line 8—8 of Fig. 3.

45 Fig. 9 is a perspective view of a blank of material suitable for folding to form a camera bellows.

Fig. 10 is a vertical section of certain operating portions of the machine and the blank in an intermediate position at the start of the folding operation.

Fig. 11 is a view similar to Fig. 10 illustrating the machine parts and the blank at a subsequent stage in the folding operation.

50 Fig. 12 is a view similar to Figs. 10 and 11 but

showing the blank and machine parts at the completion of the folding operation.

Fig. 13 illustrates the position of the blank with respect to the machine after release thereof.

Fig. 14 illustrates the completely folded bellows. 5

Referring to the drawings, the folding machine is supported by a suitable frame 15, provided with a plate 16 for supporting the folding mechanism, which may be attached to the frame by suitable means, such as bolts 17. Mounted on plate 16 10 in a suitable manner, as by bolts, are a plurality of guides 18 arranged diagonally of the plate and providing four guide-ways for the slides 19. These slides 19 may be prevented from upward movement by fitting into the grooves provided 15 between the plate 16 and the overhanging lips 18a of the guides 18 (Fig. 7). The outer ends of the slides 19 may be provided with openings 20 drilled therein to receive one end of the springs 21. The main portions of these springs 21 may be supported in suitable casing members 22 attached to the corners of the plate 16 by means of the bolts 23. Bolts 24 may be provided in the ends of these casing members 22 for bearing against the outer ends of springs 21 to adjust the effective pressure 25 thereof on the slides 19.

Slides 19 are preferably provided with camming means for restraining their movement toward the center of plate 16 under the action of springs 21. Such means may comprise rollers 25 30 rotatably mounted on shafts 26, the ends of which are held in the slides 19. The openings 27 in the slides 19 are preferably sufficiently large to freely support the rollers 25 and to receive the upper ends of the cam rods 28 having camming surfaces 28a which, in their normal position, serve to retract the slides 19 against the action of the springs 21.

The inner ends of slides 19 may be each provided with a pair of fixed upwardly extending 40 guide arms 29 which are recessed, as at 30, to form vertically extending grooves. Depending arms 31 may also be carried by the slides 19 and channeled as at 31a to form extensions of said grooves. Mounted for vertical movement in each of these grooves are a series of three vertical plates 32, 33 and 34 of varying lengths, held in place by the reticulated plates 29a fixed to the arms 29 and by the plates 39 fixed to depending arms 31. Plates 34, which are much longer than 45 the others, are provided with horizontal sections 35 to which are attached the upper folding plates 36. Additional folding plates 37 and 38 may be attached to the top of guide plates 33 and 32, respectively. 55

The lower ends of the springs 40 are attached to the lowermost portions of plates 34 and the other ends of these springs may be fixed to the depending arms 31, thus normally serving to hold the guide plates 34 and the folding plates 36 in an elevated position. Pins 41 may be fixed to plates 34 in a suitable manner to register in the notches 42 in the lower portion of plates 32 and 33 in order to also lift these plates to their uppermost position by the action of springs 40. Plungers 43 may also be mounted in the slides 19 and are normally urged forward by the action of springs 44. These plungers 43 may be provided with buffer arms 43a for cooperation with the sides of die block 47, as hereinafter described.

Except for the shapes of the inwardly extending ends of the plates 36, 37 and 38, which are varied for different folding actions, each slide 19 and the mechanism which it supports is the same and they have, therefore, been described generally without referring to any specific one of the group.

Mounted centrally between these four slides 19 and the series of plate members carried thereby is a mandrel comprising a vertically movable rod 45, one end of which passes through an opening in the strap 46 attached to underneath surface of plate 16; the intermediate portion of rod 45 passes through the die block 47 tightly fitted in an opening in plate 16. The top portion of rod 45 may be provided with an end 48 of smaller cross section than the remainder of the rod for a purpose to be described hereinafter. A pair of concentric sleeves 49, 50, carrying the rectangular shaped plates 51, 52, may be mounted concentrically with and between the rod 45 and the die block 47. Rod 45 and these sleeves 49 and 50 are preferably provided with slots 53, 54, and 55, respectively, of different lengths, to allow vertical movement thereof with respect to the pin 56 fixed in the die block 47. Pin 56 serves to prevent rotation of the rod 45 and sleeves 49 and 50. The lower portion of these sleeves 49 and 50 may be provided with suitable collars 57 and 58, respectively, and the rod 45 may be provided with a fixed collar 59. Spring 60, acting against collar 59, thus serves to hold the rod 45 and plates 51 and 52 spaced apart in their uppermost position.

Cam rods 23, for operating slides 19, are mounted for vertical movement within the sleeves 61, fixed in the plate 16. These cam rods may be provided with collars 62 to limit upward movement hereof. The springs 63 surround rods 23 within the casings 61 and are compressed between collars 62, and the removable plugs 64 which serve to hold the members in assembled position. The lower ends of these cam rods 23 are all attached to a common plate 65 by means of nuts 66a. Attached to the central portion of plate 65 is a rod 66, the lower end of which is pivotally attached to the foot treadle 67. The inner end of this treadle 67 may be pivoted in the frame 16, as at 68, and is normally held in an elevated position by the spring 69. Also pivotally attached to the treadle 67 is a second operating rod 70, pivotally connected at its other end to the link 71. One end of link 71 is pivotally mounted on frame 15 by means of the pin 72 and the other end thereof, which is bifurcated and provided with slots 73, serves to operate the vertically reciprocating rod 74. The upper end of rod 74 has an arm 75 attached thereto by means of a set screw 76. Arm 75 carries an upper die member 77 and the other end of this arm is slidably mounted on

the stationary guide rod 18 fixed to plate 16. The operating rod 74 passes freely through openings in plates 16 and 65, which serve to guide the rod 74.

The operation of the machine is as follows:

A camera bellows blank 79, such as illustrated in Fig. 9, and which has been previously formed in the shape of a frustum of a pyramid with a small metal plate 80, having an opening 81 fixed thereto, is placed over the end of rod 45 and the plates 51 and 52 so that the opening 81 in the plate 80 fits over the end 48 of the rod 45. As the foot treadle 67 is pressed downwardly, rod 66 is pulled down and plate 65 moves all four of the cam rods 23 down against the action of their respective springs 63. This allows the four slides 19 to move inwardly toward the blank under the influence of the springs 21. The side plates 36, 37, 38, are staggered vertically with respect to the central plates 51 and 52 of the mandrel and thus engage the correct portions of the sides of the bellows blank 79 to start the folding operation, as illustrated in Fig. 10. At the same time the plungers 43 and buffers 43a move inwardly and hold the lower edges of the blank firmly against the sides of die block 47.

Rod 74 has been moved down by rod 70 through link 71 at the same time although in this position of the apparatus the upper die member 77 has not yet come in contact with the top of rod 45. Upon further inward movement of the side plates 36, 37, and 38, the side walls of the bellows blank begin to assume a partially folded position, as illustrated in Fig. 11, and die member 77, having a central opening to receive the section 48 of rod 45, has moved into contact with plate 60 attached to blank 79. This necessarily reduces the overall height of the blank 79 and, as this reduction takes place, the side plates 36, 37 and 38, the central rod 45, and central plates 51 and 52 move downwardly against the action of their respective springs 40 and 60. Cam rods 23 are now out of contact with their roller followers 25 and the full action of springs 21 forces the side plates against the walls of the blank 79 in the position shown in Fig. 4.

Continued compression by die member 77 finally forces the several plates together, accompanied by a further slight inward movement of the side plates, with portions of the blank interleaved between the several plates as illustrated in Fig. 12. Figs. 4 and 5 illustrate positions which the several portions of the mechanism occupy when acting upon a blank, although the blank itself is not shown. The compression thus produced by the die member 77 assures the production of permanent folds along predetermined lines without distorting the finished bellows.

Upon release of the foot treadle 67, the mechanism is returned to its original position by the various springs and the folded blank or bellows 82 is stretched to the position shown in Fig. 13 so that it may be easily removed from the mandrel. The finished bellows has the shape and appearance illustrated in Fig. 14.

It will be seen that the construction of the mandrel and side plates provides a plurality of sets of floatingly mounted plates which are adapted to move as the sheet material of the blank is folded. This affords a positive operation and yet prevents tearing or marring of the blank, as well as assuring that every blank will be folded in the same manner.

Slides 19 may be moved inwardly by a positive camming action, if desired, although for folding

relatively flexible material, I prefer to employ springs for this purpose to avoid marring the material. Although the blanks 79 are preferably previously scored, this is not essential.

5 The side plates may be of any suitable shape either all alike, or arranged in pairs, as illustrated (Fig. 2), depending on the character of the folding operation to be performed. Where the blank does not have a plate such as 80 affixed to it, an 10 additional plate may be mounted on the upper end of rod 45. Many other modifications of the specific embodiments of my invention illustrated in the drawings may be employed as will be apparent to those skilled in the art.

15 The terms and expressions which I have employed are used as terms of description and not of limitation, and I have no intention, in the use of such terms and expressions, of excluding any equivalents of the features shown and described 20 or portions thereof, but recognize that various modifications are possible within the scope of the invention claimed.

I claim:

1. Apparatus of the character described comprising means for supporting a hollow blank of material having a polygonal shape at points thereon spaced apart from each other, and means cooperating with said supporting means for folding said blank along predetermined lines into the 30 shape of a bellows.

2. Apparatus of the character described comprising a mandrel for supporting a hollow blank of material, said mandrel contacting only portions of the blank before folding, and means cooperating with said mandrel for folding said blank along predetermined lines into the shape of a completely collapsed bellows.

3. Apparatus for folding a blank of sheet material comprising means for supporting said blank but movable in a direction at right angles to the direction of support, and means arranged to cooperate with said supporting means for pressing unsupported portions of the blank about said supporting means to fold said blank along predetermined lines into a bellows.

4. Apparatus for folding a blank of sheet material having a polygonal shape comprising means for supporting said blank but movable in a direction at right angles to the direction of support, and means arranged to cooperate with said supporting means for folding said blank along predetermined lines, said last named means being movable in a direction at right angles to the main line of folding.

5. Apparatus for folding a hollow blank of sheet material comprising means movable longitudinally of the blank for supporting said blank at spaced points throughout the circumference thereof, and means arranged to cooperate with said supporting means for folding said blank about said supporting means along predetermined lines.

6. Apparatus for folding a hollow blank of sheet material comprising means movable longitudinally of the blank for supporting said blank, means also movable longitudinally of the blank arranged to cooperate with said supporting means for folding said blank about said supporting means along predetermined lines, and means for moving said two means longitudinally of the blank 70 simultaneously to assist the folding action thereof.

7. In apparatus of the character described, a mandrel comprising a plate-like member movable in a direction substantially normal to its plane for supporting the interior of a hollow blank 75 throughout its circumference, and means for co-

operating with said mandrel to fold said blank about said mandrel.

8. Apparatus for folding a blank of sheet material comprising non-rotatable means for supporting said blank, and means arranged to cooperate with said supporting means for folding said blank along predetermined lines, said last named means comprising a plurality of plate-like members movable edgewise and also movable in a direction substantially normal to their planes. 10

9. In apparatus of the character described, a mandrel comprising a plate-like member movable in a direction substantially normal to its plane, means for preventing rotation of said member, and means for cooperating with said mandrel to 15 fold a blank of sheet material placed on said mandrel, said means comprising a plurality of plate-like members movable edgewise and also movable in a direction substantially normal to their planes. 20

10. In apparatus of the character described, a mandrel comprising a plate-like member movable in a direction substantially normal to its plane, means for cooperating with said mandrel to fold a blank of sheet material placed on said mandrel, 25 said means comprising a plurality of sets of substantially parallel plate-like members movable edgewise and also movable in a direction substantially normal to their planes, and means for moving the members of said cooperating means 30 edgewise toward said mandrel.

11. In apparatus of the character described, a mandrel comprising a plate-like member movable in a direction substantially normal to its plane, means for cooperating with said mandrel to fold 35 a blank of sheet material placed on said mandrel, said means comprising a plurality of plate-like members movable edgewise and also movable in a direction substantially normal to their planes, means for moving the members of said cooperating 40 means edgewise toward said mandrel, and means for suddenly moving the members of said mandrel and cooperating means in a direction substantially normal to the planes thereof to complete the folding operation. 45

12. In apparatus of the character described, a mandrel comprising a plate-like member movable in a direction substantially normal to its plane, means for cooperating with said mandrel to fold a blank of sheet material placed on said mandrel, 50 said means comprising a plurality of plate-like members movable edgewise and also movable in a direction substantially normal to their planes, means for moving the members of said cooperating means edgewise toward said mandrel, and 55 a die member for subsequently striking a blow to move said plate-like members toward each other.

13. In apparatus of the character described a mandrel comprising a plate-like member adapted 60 to move in a direction substantially normal to the plane thereof, a plurality of sets of plate-like members, constructed and arranged to move relative to each other in a direction substantially normal to their planes, and means for moving 65 said sets of members edgewise toward said mandrel.

14. In apparatus of the character described a mandrel comprising a plate-like member adapted to move in a direction substantially normal to the 70 plane thereof, a plurality of sets of plate-like members, constructed and arranged to move relative to each other in a direction substantially normal to their planes, means for moving said sets of members edgewise toward said mandrel, 75

and die means for subsequently moving all of said plate-like members together.

15. Apparatus as defined in claim 9 including spring means for urging said plate-like members apart.

16. Apparatus as defined in claim 13 including spring means for urging the plate-like members of each set apart.

17. Apparatus as defined in claim 13 in which 10 the plate-like members of each set are normally staggered with respect to the mandrel member.

18. Apparatus for collapsing a hollow blank of sheet material into a bellows comprising a mandrel having a plate for supporting said blank 15 which plate is movable in a direction substantially normal to its plane, a plurality of slides, a plurality of sets of plate members supported on said slides for movement in a direction substantially normal to their planes, means for 20 moving said slides toward said mandrel, and means for moving said plate members towards each other after they have engaged said blank.

19. A method of folding a hollow polygonal shaped blank of material comprising exerting 25 pressure on both the inside and outside of said blank at points spaced apart from each other to start said folding, and subsequently compressing said blank by a force applied in a direction substantially at right angles to the direction of said 30 pressure to completely collapse said blank into the form of a bellows.

20. Folding apparatus comprising a mandrel, folding means movable toward said mandrel, spring means for urging said folding means toward said mandrel, cam means for controlling the movement of the folding means by said spring means, and means for moving said mandrel and folding means in a direction substantially at right angles to the first mentioned direction of movement of said folding means.

21. Folding apparatus comprising a mandrel, 10 a plurality of sets of folding members, and means for simultaneously moving said sets of folding members towards said mandrel, said members and mandrel being resiliently mounted for movement towards each other in a direction at right 15 angles to the first mentioned direction of movement of said folding members during a folding operation.

22. Apparatus as defined in claim 3 in which means is provided for applying pressure longitudinally of the blank to complete the folding of 20 said blank.

23. Apparatus as defined in claim 9 in which means is provided for resiliently urging the plate-like members apart.

24. The method as defined in claim 19 in which the complete collapse of the blank into a bellows is obtained by sharply striking the top of the partly folded blank.

MAURICE M. BALSAM. 30
